Primary Examiner — Karen E Eldridge Powers

(57) **CLAIM**

The ornamental design for a facial cleaning brush, as shown and described.

DESCRIPTION

FIG. 1 is a front, top and right side perspective view of a facial cleaning brush showing my new design;

FIG. 2 is a rear, bottom and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof;

FIG. 8 is a top plan view thereof; and,

FIG. 9 is an enlarged view of portion 9 shown in FIG. 1. The broken lines in the drawings depict portions of the facial cleaning brush that form no part of the claimed design.

1 Claim, 9 Drawing Sheets
